EXPANSIBLE SHOE TREE

Arthur Schoshusen, West Somerville, Mass.

Application April 30, 1946, Serial No. 666,074

3 Claims. (Cl. 12—128.2)

1

This invention relates to improvements in shoe trees and more particularly to shoe trees having provision for spreading the shoe form after its insertion in a shoe thereby to facilitate insertion of the shoe form while it is in a contracted state and to enable the shoe form, by subsequent spreading within the shoe, to effectively maintain the shoe substantially in its original shape. The invention provides improvements which simplify the construction of such shoe trees and which improve their operative effectiveness.

It is among the objects of my invention to provide a shoe tree having a fore-part shoe form which is laterally resiliently contractible and spreadable and having a longitudinally resiliently contractible and expansible part for engaging within the counter of a shoe with interconnection between the fore-part shoe form and the counter-engaging part whereby, with the fore-part shoe form held relatively stationary, as when it is in laterally spread condition within a shoe, manual pressure applied to the counter-engaging part longitudinally in direction away from the fore-part, causes contraction of the fore-part so that it more readily may be withdrawn from a shoe.

Another object is to provide a shoe tree having a fore-part shoe form which is laterally resiliently contractible and spreadable and having a part for engaging within the counter portion of the shoe and longitudinally resiliently contractible and expansible, with means interconnecting the fore-part shoe form and the counter-engaging portion whereby the fore-part form may be supported in longitudinally projected position by means of said counter-engaging part and said interconnecting means.

A further object is to provide a shoe tree having a fore-part form and an axially recessed handle for engaging endwise within the counter of a shoe, with a stiff bar connecting the fore-part form and the handle and supporting the handle for resilient yielding thereof toward the fore-part form.

It is, moreover, my purpose and object generally to improve the structure and operation of shoe trees.

In the accompanying drawing:

Fig. 1 is a top plan view of a shoe tree embodying features of my invention;

Fig. 2 is a cross-sectional view on line 2—2 of Fig. 1;

Fig. 3 is a cross-sectional view on line 3—3 of Fig. 2 showing the shoe tree in a shoe whose upper is shown in cross-section;

2

Fig. 4 is a top plan of the shoe tree with its fore-part form shown contracted within a shoe whose vamp is shown in cross-section, the handle end of the shoe tree being disengaged from the rear part or counter of the shoe and the arrow indicating that withdrawal force is applied to the handle in the direction of the arrow to cause said contraction of the fore-part form within the shoe; and

10 Fig. 5 is a cross-sectional view on line 5—5 of Fig. 1.

Referring to the drawing, my improved shoe tree comprises a fore-part form which consists of two sections 10, 12 which have generally parallel confronting surfaces and which together provide a general contour for substantially filling the interior space within the vamp of a shoe. Each section 10, 12, at the confronting surfaces of the sections, is provided with a recess 14, 16 for seating the opposite end portions of a coil spring 18 which constantly biases the sections apart. The spring may be variously located along the sections, being herein shown somewhat closer to the rear ends of the sections than to their toe ends, and a guide pin 20, conveniently in the form of a headed nail, may be driven into the section 10 with a substantial part of the nail, including its head 22, protruding and engaging loosely in a recess 24 in the section 12. Recess 24 has depth 25 for accommodating the protruding portion of the nail when the sections 10, 12 are closed together against the bias of spring 18.

It is a feature of the invention that a ring 26 of metal or other suitable material is driven into 35 the entrance to recess 24 for constituting a guide for the pin 20 as the sections move relatively toward and from each other and for serving as a stop for limiting the spreading movement of the sections. It will be observed that the described 40 guiding of the sections is attained without any hole or part extending through outer surfaces of the sections 10, 12, as compared with prior proposals which require a countersunk hole in the exterior surface of at least one of the fore-part form sections. According to the invention, the ring 26 may be slipped on the shank of the nail prior to driving the nail into the section 10. After the nail has been driven into section 10 to anchor it relative to section 10, the ring 26, 50 while encircling the nail, may be driven into the entrance to recess 24 thereby to anchor the ring in section 12. The nail preferably extends relatively loosely through the ring 26 to avoid binding if and when the sections may have unequal 55 spread fore and aft.

The rear end of each form section 10, 12 is horizontally slotted as at 28, 30, and the rear confronting portions of the sections are cut away as at 32, 34 for a purpose which later will appear.

According to the invention, the form sections 10, 12 have a toggle connection to one end of a stiff bar 36 whose other end carries the tubular handle 38 whose outer end is provided with a rounded knob 40 for seating within the counter of the shoe, the handle being resiliently yieldable along bar 36 to facilitate arrangement of knob 40 within the counter after the fore-part form sections have been inserted in the vamp.

The toggle connection to bar 36 comprises a U-shaped member whose arms 42 engage opposite sides of the bar 36 at its inner end, the bridge 44 of the U-element underlying the lower edge of bar 36. The bar is pivotally connected to the arms 42 of the U-member by a pin 46 so that the bar and its handle may be swung on a pivot pin 46 in one direction relative to the U-member to bring the bar and handle over upon the fore-part form sections 10, 12 but is restrained against movement in the opposite direction beyond the plane of the bridge 44 of the U-member. A pivot stud 48 depends from the bridge 44 of the U-member, and a pair of toggle links 50, 52 have their inner ends pivotally connected to stud 48 and have their outer ends extending respectively into the horizontal slots 28 and 30 in the rear ends of the form sections 10, 12, each being pinned within its slot by a pin or nail 54 which preferably will be driven into the under surface of each section 10, 12 to extend through a suitable hole in the inner end of each toggle link 50, 52. One toggle link has a lug 56 thereon for limiting spreading of the links to less than an on-center position as shown in Figs. 1 and 3. This limits the permissible spread of the form sections 10, 12 at their rear portions, and the head of pin 20 engaging ring 26 limits spreading of the sections at their forward portions.

According to the invention, the tubular handle 38 economically may be fashioned by a mere turning of a piece of wood or other suitable material, and be then provided with the axial bore 58 which terminates within the knob 40 of the handle. It is a feature that this economical handle quickly and easily may be mounted resiliently on bar 36 with a spring 60 within bore 58 engaging between handle 38 and bar 36 constantly urging them apart, yet bar 36 may be a low cost bar which is flat from end to end. I utilize a headed bolt whose shank 62 may be without threads and whose head 64 is slotted at 66 for reception of the outer end of bar 36.

In assembling the device, the spring 60 is inserted in the bore followed by the bolt, shank first, so that the shank extends loosely within the coils of the spring with the outer coil engaging the head 64 of the bolt. At this stage, the head 64 of the bolt may project out of the bore so that the end of bar 36 conveniently may be seated loosely in its groove 66. The bar 36 is longitudinally slotted at 68, and the inner end of the handle may have a transverse hole 70 therethrough. Hence, with bar 36 seated in the groove 66 of the bolt, the bar may be pressed into the handle bore, compressing spring 60 therein, until the slot 68 of the bar can be brought opposite the transverse hole 70 after which a pin 72 may be secured in position extending in hole 70 and through slot 68. When pressure is released,

the spring biases the handle 38 and bar 36 relatively so that pin 72 normally is maintained at the left hand end of slot 68 as clearly shown in Fig. 2.

When my improved shoe tree is to be inserted in a shoe, the fore-part form sections 10, 12 preferably will be manually squeezed together to facilitate their insertion in the vamp of the shoe. However, after the sections have been fairly well started into the shoe, subsequent inserting force may be applied through handle 38 and bar 36, with the fore-part spring 18 acting to resiliently spread the form sections laterally and with the toggle arms 50, 52 applying a positive spreading force, so that the sections 10, 12 in slipping into the shoe effectively iron out wrinkles in the shoe upper. After the fore-part sections 10, 12 have been finally positioned in the vamp of the shoe, handle 38, with its spring 60 held compressed, may be lowered to bring its knob 40 within the counter of the shoe, after which the handle may be released to permit its spring 60 to forcibly press knob 40 against the back interior of the counter while exerting also a resilient thrust on the fore-part sections which puts the entire shoe under longitudinal tension while the sections 10, 12 apply lateral pressures which put the vamp of the shoe under constant lateral tension so long as the shoe tree remains in the shoe.

A feature of advantage is that the shoe tree may be withdrawn from a shoe without pulling and tugging to get the spread fore-part sections free. According to the invention, the handle 38 and its shoe-engaging knob 40 may be easily lifted out of the counter region of a shoe by merely pressing the handle toward the fore-part to compress its spring enough to free knob 40. The fore-part sections 10, 12 also may be easily withdrawn by applying a rearward pull on the handle 38 or bar 36 which, through the toggle, moves the sections 10, 12 laterally toward each other so that they readily and easily slide out of the shoe as a further rearward and somewhat upward pull is applied through handle 38.

45 I claim as my invention:

1. A shoe tree comprising a pair of fore-part form sections constantly biased in direction to spread them laterally apart, a toggle for operating said form sections laterally toward and from each other, said toggle comprising a rigid bar, a pair of toggle links pivotally mounted at one end of the bar and each link pivotally connected to a different one of the form sections, a handle slidably mounted on the other end of said bar and biased in direction away from the toggle end of the bar, means for limiting movement of the handle in both directions on the bar, said toggle being adapted to move the fore-part sections laterally toward each other in response to a pull on said handle while the fore-part sections are held against movement in the general direction of the pull.

2. A shoe tree comprising a pair of fore-part form sections constantly biased in direction to spread them laterally apart, each said section having a slot in its rear end generally in a plane parallel with the plane of the under surface of said sections, a rear-part form, a rigid thrust bar connecting the rear-part form with the fore-part form sections, said bar having a toggle connection to the fore-part sections including a pair of toggle links pivoted on said bar with each link extending into and pivotally secured within a different one of said slots.

75 3. A shoe tree comprising means for fitting

within and shaping the vamp of a shoe, a rigid generally flat bar connected to said means, a handle resiliently mounted on said bar and having a portion for engaging within the counter of a shoe, said handle being formed with a generally cylindrical body having a knob at each end and having an axial cylindrical bore terminating within the outer-most knob, a coil spring in said bore, a spring engaging member having a shank loosely engaging in end convolutions of said spring and having a head against which the end-most spring convolution engages, said head having a groove therein and the outer end of said generally flat bar being loosely engaged in the groove, said bar having a slotted outer end portion extending within said bore of the handle, and a pin extending transversely of the handle and through the slot in said bar, and said engagement of the end of the generally flat bar in the groove in the head

of said spring engaging member maintaining the engaged end of the flat bar against lateral movement in said cylindrical recess of the handle in directions axially of said pin.
